UNITED STATES PATENT OFFICE.

ADAM SPANIAK, OF BALTIMORE, MARYLAND, ASSIGNOR OF ONE-HALF TO WILLIAM I. PRICE, OF BALTIMORE, MARYLAND.

DESIGN FOR AN ELECTRIC-BULB HOLDER.

57,942.

Specification for Design.

Patented May 17, 1921.

Application filed October 8, 1920. Serial No. 415,702. Term of patent 7 years.

To all whom it may concern:

Be it known that I, ADAM SPANIAK, a citizen of the United States, residing at Baltimore, in the city of Baltimore and State of Maryland, have invented a new, original, and ornamental Design for an Electric-Bulb Holder, of which the following is a specification, and illustrated in the accompanying drawing, forming a part hereof, wherein—

Figure 1 is a side elevation of my electric bulb holder as shown,

Fig. 2 is a front elevation of my electric bulb holder as shown, and

Fig. 3 is a rear elevation of my electric bulb holder as shown.

I claim:

The ornamental design for an electric bulb holder as shown.

ADAM SPANIAK.

Witnesses:

WILLIAM I. PRICE,
ESTHER FEINSTEIN.
